HAY RACK

Thomas Edgar Sikes, Greensboro, N. C.

Application January 27, 1941, Serial No. 376,219

4 Claims. (Cl. 211—29)

This invention relates to hay racks, and the like, and has for one of its objects the production of a simple and efficient foldable rack specially constructed for supporting soy beans, peanuts, legume hay, etc., in a field for the purpose of drying.

A further object of this invention is the production of an efficient locking means for holding the legs of the rack in a braced and set-up position.

Other objects and advantages of the present invention will appear throughout the following specification and claims.

In the drawings:

Figure 1 is a side elevational view of the rack in a set-up position;

Figure 2 is a top plan view of the pivot connection for the legs, the legs being broken away;

Figure 3 is a horizontal sectional view taken on line 3—3 of Figure 1;

Figure 4 is a sectional view taken on line 4—4 of Figure 2;

Figure 5 is a fragmentary perspective view of a portion of one leg and brace, showing the locking means therefor;

Figure 6 is a fragmentary perspective view of the outer end of one of the braces;

Figure 7 is a side elevational view of the rack in its folded position;

Figure 8 is a vertical sectional view taken on line 8—8 of Figure 7;

Figure 9 is a horizontal sectional view taken on line 9—9 of Figure 7.

By referring to the drawings, it will be seen that 10 designates the head of the rack which is preferably hollow and square in cross section. A brace-carrying leg 11 and a brace-engaging leg 12 are pivotally secured on opposite sides of the head 10 by means of a journal pin 13. A second brace-carrying leg 14 and a second brace-engaging leg 15 are pivotally secured on opposite sides of the head 10 by means of a journal pin 16 extending at right angles to the movement of swing of the legs 14 and 15. The legs 11, 12, 14 and 15 are preferably made of a light angle iron structure of suitable gauge and size, as shown.

An angle iron brace 17 is pivotally secured at 18 to the leg 11, and the outer end of this brace 17 is provided with a socket 19 in the portion 20 of the brace which extends in a horizontal position when the rack is set-up. A lug 21 is formed at the extreme outer end of the brace 17 extending in the same plane as the portion 20. The lug 21 is provided with a notch 22 in its inner edge adjacent the socket 19. The lug 21 is provided

also with a retaining arm receiving notch 23 formed in the outer edge thereof, the notches 22 and 23 being formed adjacent the portion of the angle brace 17 which extends at substantially right angles to the portion 20.

A brace 24 is pivotally secured, as at 25, to the leg 14 and this brace 24 is provided with a lug 23^a formed similarly to the lug 21. The brace 24 is a duplicate in structure of the brace 17. A plurality of retaining arms 26 are pivotally secured to the legs 11, 12, 14 and 15, as shown in Figure 1, the inner ends of the retaining arms 26 being adapted to abut against the respective legs when the arms are swung outwardly, as shown in Figure 1, to hold the arms in an extended position to assist in supporting the weight of hay, soy beans, peanut vines and the like when stacked upon the rack. These retaining arms 26 may be folded inwardly toward the legs in the manner shown in Figure 7, and the legs may also be folded to the position shown in Figure 7 to provide a compact structure to facilitate shipment and storage. The braces 17 and 24 may also be folded longitudinally of their respective carrying legs so as to lie flat against the same in the manner shown in Figures 8 and 9 when the device is in a folded position. When the rack is set up the braces 17 and 24 are adapted to extend in crossed overlapped relation such as is shown in Figures 1 and 3, the outer end of the brace 17 being adapted to engage the leg 12 and the outer end of the brace 24 being adapted to engage the leg 15, as shown.

The retaining arms 26 are preferably formed of an angle iron structure, as illustrated in detail in Figure 5, and the lower retaining arm 26 carried by the leg 12 and the lower retaining arm 26 carried by the leg 15 are adapted to fit within the notches 23 of the lugs 21 and 23^a respectively to hold the respective braces 17 and 24 against accidental release with respect to the supporting legs of the rack. It should be understood that the socket 19 for example, shown in Figure 5 with respect to the brace 17 is of sufficient size to permit the leg 12 to fit within the socket 19 and one flange of the leg 12 is then moved into the notch 22 to lock the brace 17 against lateral movement. The brace 17 is then forced downwardly to cause the lower retaining arm 26 shown in Figure 5 to engage the notch 23 and thereby lock the outer end of the brace 17 in firm engagement with the leg 12 in the manner shown in Figure 5. As stated above, the outer end of the brace 24 is connected to the leg 15 in the same manner as that described and il-

lustrated in Figure 5. It will be seen by carefully considering the drawing that all of the retaining arms 26 are provided with inner end portions cut on an incline at a proper angle to support the retaining arms 26 in an approximately right-angularly extended relation with respect to the supporting legs when these retaining arms 26 are swung outwardly.

The legs 11 and 12 are pivotally secured to the head 10 and when the device is set-up, the legs 11 and 12 are spread apart at their lower ends and the legs 14 and 15 are also spread apart at their lower ends in a direction at right angles to the legs 11 and 12 to provide a substantially cone-shaped rack. The braces 17 and 24 are properly secured at their outer ends to the respective legs 12 and 15 in the manner previously described and the outer ends of the braces 17 and 24 are brought into engagement with the lower retaining arms 26 carried by the respective legs 12 and 15, thereby firmly locking the rack in a set-up position. All of the retaining arms 26 are then swung outwardly until their inner ends abut against the respective supporting legs. These retaining arms by extending upwardly at an incline and outwardly with respect to the legs will provide efficient supports or hooks to be engaged by material such as soy beans, peanut vines, hay, and the like, and to support this material in a stack for the purpose of drying. When the rack has performed its service and it is desired to transport the rack to another place, or to store the same for future use, the braces 17 and 24 are released from the respective legs 12 and 15 by swinging the braces upwardly so as to release the same from the retaining arms whereupon the braces may be detached from the legs 12 and 15. By moving the legs 12 and 15 out of the notches formed adjacent the lugs 21 and 23^a, such for instance as the notch 19 shown in Figure 5. The braces 17 and 24 may be then swung to extend parallel to the supporting legs 11 and 14, the retaining arms being swung inwardly to lie flat within the channels of their respective legs, and the legs 11, 12, 14 and 15, may then be swung to lie substantially flat against each other in the position shown in Figures 7 and 9, thereby accommodating the rack to a small amount of space.

It should be understood that certain detail changes in the construction may be employed without departing from the spirit of the invention, so long as such changes fall within the scope of the appended claims.

Having described the invention, what is claimed is:

1. A knock-down rack of the class described comprising a plurality of pivotally connected legs mounted for swinging movement to provide a substantially cone-like supporting rack when in a set-up position, braces for supporting the legs in a set-up position, pivotally mounted outwardly swinging retaining arms carried by said legs, and said braces having means engageable by some of said retaining arms for locking said braces against accidental detachment from said legs.

2. A knock-down rack of the class described comprising a head, a pair of legs of an angle iron structure pivotally secured to said head and adapted to swing in opposite directions, a second

pair of legs pivotally secured to said head at right angles to the first mentioned legs, the legs of the second pair being adapted to swing away from each other, the legs when in a set-up position defining a substantially cone-shaped frame-work, a plurality of retaining arms pivotally secured to said legs, a brace pivotally secured to one leg of each pair and adapted to extend transversely from one leg of one pair to the other leg of the same pair, each brace having a locking means at its outer end for engaging the companion leg of each pair, said locking means comprising a lug formed at the outer end of the brace, the brace having a socket formed adjacent the lug for receiving a leg, the lug having a notch formed upon its inner edge for receiving the angle portion of a leg, and the lug also having a notch formed in its outer edge for receiving one of said retaining arms to hold the brace against independent movement with respect to its engaging leg.

3. A knock-down rack of the class described comprising a head, a pair of legs of an angle iron structure pivotally secured to said head and adapted to swing in opposite directions, a second pair of legs pivotally secured to said head at right angles to the first mentioned legs, the legs of the second pair being adapted to swing away from each other, the legs when in a set-up position defining a substantially cone-shaped frame-work, a plurality of retaining arms pivotally secured to said legs, a brace pivotally secured to one leg of each pair and adapted to extend transversely from one leg of one pair to the other leg of the same pair, each brace having a locking means at its outer end for engaging the companion leg of each pair, said locking means comprising a lug formed at the outer end of the brace, the brace having a socket formed adjacent the lug for receiving a leg, the lug having a notch formed upon its inner edge for receiving the angle portion of a leg, the lug also having a notch formed in its outer edge for receiving one of said retaining arms to hold the brace against independent movement with respect to its engaging leg, and each retaining arm having an inclined inner end adapted to abut against its supporting leg to provide a stop to hold the retaining arm in an extended position at an angle to the longitudinal axis of its supporting leg when the device is in a set-up position.

4. A rack of the class described comprising a pair of pivotally connected legs adapted to swing in opposite directions, a second pair of pivotally secured legs also adapted to swing in opposite directions, means for connecting the pairs of legs together to mount the pairs at right angles to each other, braces for holding the legs of each pair in spread-apart relation, the braces being foldable with respect to the legs, and retaining arms pivotally secured to the legs and adapted to be moved outwardly of the legs, the retaining arms and the braces all being foldable to lie flat and longitudinal of the legs, and the legs being adapted to be moved to extend in parallel relation with respect to each other to accommodate the rack in a minimum amount of space when the rack is in a knocked-down position.
